C. H. ANDERSON.
WINDOW SASH CONSTRUCTION.
APPLICATION FILED JUNE 28, 1916.

1,273,716.

Patented July 23, 1918.

UNITED STATES PATENT OFFICE.

CHARLES H. ANDERSON, OF CINCINNATI, OHIO.

WINDOW-SASH CONSTRUCTION.

1,273,716.

Specification of Letters Patent. Patented July 23, 1918.

Application filed June 28, 1916. Serial No. 106,408.

To all whom it may concern:

Be it known that I, CHARLES H. ANDERSON, a citizen of the United States, and a resident of Cincinnati, in the county of Hamilton and State of Ohio, have invented certain new and useful Improvements in Window-Sash Construction; and I do hereby declare the following to be a full, clear, and exact description of the invention, such as will enable others skilled in the art to which it appertains to make and use the same.

This invention relates to improvements in car windows and more particularly to sash locking means and the mountings therefor, one object of the invention being to provide a structure in which a metal corner bracket may be utilized to provide improved mountings for the sash locking and lifting means and thereby obviate the defects and objections incident to the mounting of locking means on wooden sash frames.

With this and other objects in view, the invention consists in certain novel features of construction and combinations of parts as hereinafter set forth and pointed out in the claims.

In the accompanying drawings; Figure 1 is a face view showing the corner portion of a window sash embodying my improvements; Fig. 2 is an edge view; Fig. 3 is a longitudinal sectional view through the lower right hand corner bracket of a window sash and showing the mountings of the lifting and locking means; Fig. 4 is a view on the line 4-4 of Fig. 3; Fig. 5 is a view on the line 5-5 of Fig. 3; Fig. 6 is a view on the line 6-6 of Fig. 3, and Fig. 7 is a separate view of the finger lift plate.

1 represents the lower right hand corner bracket of a window sash and the same is adapted for connection with the rails of the sash as fully set forth in my application for patent filed concurrently herewith and designated by serial No. 106,407. The corner bracket 1 comprises a hollow metal structure, in the chambers of which suitable insulating material 2, may be packed.

The lower horizontal member of the corner bracket is formed with a pocket 3, in which a removable backing 4 of cork or other suitable material may be placed. At or near the top of the pocket 3, the end walls of the latter are made with grooves 5 to receive the ends of a finger lift plate 6, said finger being inserted into the pocket so that its inner edge

will bear against the cork backing 4. The projecting portion of the finger lift plate is made with shoulders 7 to rest against the outer face of the bracket. The lift plate is thus made separate from the bracket and may be inserted after the sash has been subjected to the action of a sand-paper machine. This sand-papering of the sash could not be readily accomplished if the finger lift were made integral with the bracket, — hence the desirability of making it as a separate part.

Above the pocketed portion of the bracket, the latter is made with a bore 8 into which the shank 9 of a sash lock or presser foot 10 is mounted, and the end face of the bracket is made with a recess 11 to receive said lock or presser foot, — said recess being open at one side to permit the lock or presser foot to reach the window frame or a suitable engaging device thereon. The shank 9 of the presser foot is provided with a shaft 12 which extends through the bore 8 and is revolubly mounted in a smaller bore 13 in the corner bracket. A coiled spring 14 encircles the shaft 12 and one end of this spring is inserted into a socket 15 in the shank 9, the other end of said spring being made with a straight portion 16 to enter a groove 17 in the wall of the bore 8.

The corner bracket is made with a pocket 18 immediately over the pocket 3 and the finger lift plate 6, for the accommodation of a finger lever 19, the latter being made with a sleeve 20 through which the presser foot shaft 12 passes. The sleeve portion of the finger lever is secured to the shaft 12 by means of a screw 21, and to permit ready access to this screw after the parts shall have been assembled and the shaft turned to apply tension to the spring, the finger lift plate 6 is made with a hole 22 communicating with the pocket 18.

My improved locking and lifting devices can be easily and quickly assembled; are securely and effectually mounted within the metal corner bracket, and are not liable to deterioration or to get out of order.

Slight changes might be made in the details of construction of my invention without departing from the spirit thereof or limiting its scope and hence I do not wish to restrict myself to the precise details herein set forth, except as limited by the claims.

Having fully described my invention what

I claim as new and desire to secure by Letters-Patent, is:—

1. In a window sash construction, the combination with rails thereof, of a separate metal corner bracket secured to said

5 rails and constituting a corner portion of the sash, and a sash lock device mounted within and carried by said corner bracket.

2. In a window sash construction, the combination with rails thereof, of a separate corner bracket secured to said rails and constituting a corner portion of the sash, said corner bracket comprising a hollow metal structure having a bore therein, a sash 15 lock having a part mounted in said bore, and thumb lever secured to the part mounted in said bore.

3. The combination with rails of a sash and a separate metal corner bracket constituting a part of the sash and provided with a bore having a groove in the wall of said bore, of a sash lock device having a part passing through said bore, a spring within said bore having one end connected with the 25 lock device and having its other end disposed in said groove, and a thumb lever connected with said lock device.

4. The combination with rails of a sash and a separate metal corner bracket constituting a part of the sash and having a bore therein, of a sash lock device having a part mounted to turn in said bore, a spring for turning the lock device in one direction, said corner bracket having a pocket, and a finger 35 lever entering said pocket and secured to a part of the lock device within the corner bracket.

5. The combination with rails of a sash and a separate metal corner bracket constituting a part of the sash and having an open 40 pocket therein, of a finger lift securely fixed in said pocket at the upper side thereof.

6. The combination with rails of a sash

and a separate metal corner bracket constituting a part of the sash and having a pocket 45 provided in its end walls with grooves, of a lift plate having its ends inserted in said grooves.

7. The combination with rails of a sash and a separate metal corner bracket constituting a part of the sash and having a pocket, of a finger lift secured in said pocket and a sash lock device having a part mounted within the bracket above said finger lift.

8. The combination with rails of a sash 55 and a separate metal corner bracket constituting a part of the sash and having two open pockets one above the other, of a finger lift secured in the lower pocket, a sash lock device having a part mounted within the 60 bracket and passing through the upper pocket, and a finger lever entering the upper pocket and secured to the part of the lock device which passes through said upper pocket.

9. The combination with rails of a sash and a separate metal corner bracket constituting a part of the sash and having two 65 pockets, one above the other, a sash lock device having a part mounted in the bracket 70 and passing through the upper pocket, a finger lever entering the upper pocket, fastening means securing said finger lever to the part of the locking device passing through said upper pocket, and a finger lift secured 75 in the lower pocket and having a hole communicating with the upper pocket to permit the insertion of a tool to be applied to said fastening means.

In testimony whereof, I have signed this 80 specification in the presence of two subscribing witnesses.

CHARLES H. ANDERSON.
